BUOYANT ROLLER BOAT

Joseph Fitzgibbon, West Easton, Pa.

Application August 20, 1934, Serial No. 740,685

1 Claim. (Cl. 115—19)

This invention relates to improvements in boats wherein buoyant propellers are employed.

With boats having a hull immersed in the water, there is a great deal of sliding friction and the higher the speed of the boat, the greater the friction and the greater the resistance is to forward movement offered by the water.

An object of this invention is to provide a buoyant boat in which the rolling friction of rotary multiple keels or rollers is substituted for the sliding friction of a hull having a single fixed keel.

Another object of this invention is to provide a buoyant boat wherein the hull is supported upon cylindrical buoyant propellers which have sufficient displacement to maintain them together with the superimposed weight of the boat mostly above the surface of the water when at rest, and to raise the boat above the water when in motion.

Another object of this invention is to provide a buoyant boat embodying buoyant cylindrical propellers mounted in outboard bearings on opposite sides of the hull adjacent the bow and a buoyant cylinder mounted in outboard bearings at the stern, all of the said cylinders being rotatable about horizontal axes transverse to the direction of travel of the boat.

Another object of this invention is to provide a buoyant boat embodying buoyant cylindrical propellers rotatably mounted on opposite sides of the hull adjacent the bow and having thereon oppositely directed helical propelling blades so formed as to drive the water away sideways from the hull and exercise a centralized raising action on the bow end of the boat when the propellers are rotated.

With the above and other objects in view, the invention will be hereinafter more particularly described and the combination and arrangement of parts will be shown in the accompanying drawings and pointed out in the claim which forms part of this specification.

Reference will now be had to the drawings, wherein like numerals of reference designate corresponding parts throughout the several views, in which:

Figure 1 is a side elevation of a buoyant boat according to this invention.

Figure 2 is a cross-sectional view, the section being taken as on line 2—2 in Figure 4.

Figure 3 is a cross-sectional view, the section being taken as on line 3—3 in Figure 4.

Figure 4 is a plan view of the buoyant boat.

In the illustrated embodiment of the invention, the several views show a buoyant boat 10 com-

prising a hull 11 having a buoyant cylinder 12 rotatably mounted outboard in bearings 13 behind the stern 14, and two buoyant cylindrical propellers 15, respectively positioned on opposite sides of the hull 11 adjacent the bow 16.

The propellers 15 have been secured to a driving shaft 17 extending transversely through the hull. The propellers 15 comprise buoyant cylinders 18 having helical blades 19 attached at one edge of the outer faces of the cylinders 18 and project outwardly therefrom. The propeller blades 19 on the respective cylinders 18 face in opposite directions with respect to the hull 11 and drive the water away sideways from the hull, and when the propellers are rotated, the blades 19 produce a lifting effect which causes diminished immersion sufficient to raise the hull above the water. The propellers 15 are rotatably mounted in bearings 20 and 21, best shown in Figure 3.

The cylinder 12 at the stern and the cylinders 18 at the bow are hollow and act as buoyant floats which are partly immersed in the water. The floatative power of the cylindrical floats should be sufficient to maintain the hull 11 mostly above the surface of the water when at rest, and to raise the hull out of the water when in motion so that the only resistance to motion of the hull is that offered by the air.

As shown in Figures 2 and 4, the hollow buoyant cylinder 12 has corrugations 22 on its cylindrical surface, the said corrugations being positioned parallel with the axis of said float and provide a more positive means to cause rotation of the cylinder 12 when the boat 10 is set in motion by the action of the propellers 15.

Under operating conditions, the rudder diverts or throws the water in an inclined direction rearwards of the boat. As best shown in Figure 2, the buoyant rear cylinder 12 has conically shaped smooth surfaced ends, the pointed smooth surfaced ends permit the diverted water to move along an inclined surface on the float and get away from the boat. The pointed ends thus serve to facilitate steering of the boat.

Rotary motion may be imparted to the driving shaft 17 and the propellers 15 by means of an engine 23 which may be provided with a pinion gear 24 meshing with a gear 25 mounted on the shaft 17. As shown in Figure 1, a rudder 26 at the stern end of the boat extends downward and a rudder post 27 is provided at its upper end with a steering arm 28 for actuating the rudder. As shown, the rudder 26 is interposed between the bow and stern floats.

55

It is to be noted that two or more helical blades may be mounted on each buoyant cylinder 18, the said blades extending from one end face of a cylinder to the other end face, but only around 5 one half the circumference of the said cylinder.

The bearings 21 for the buoyant propellers 15 are supported from outboard frames 29 and the bearings 13 for the buoyant cylinder 12 are supported from an outboard frame 30. It will be 10 noted that the large transverse distance between the ends of the propellers 15 tends to augment the stability of the boat and enables greater speeds to be reached in safety in boats of small or very large capacity.

15 I claim:

In a buoyant float-supported boat of the class described, comprising two buoyant cylindrical propellers secured to a driving shaft extending transversely through the hull, said shaft being 20 mounted in outboard bearings, said propellers being on opposite sides of the hull at the bow, said

propellers including oppositely directed helical propelling blades extending around one-half the circumference and co-extensive with the length of said cylinders, said propeller blades being designed to drive the water away transversely from opposite sides of said hull and automatically exert an augmented centralized raising action sufficient to raise the bow end of said boat above the water when in motion, a rudder at the stern end of said boat, a buoyant cylindrical float rotatably mounted in outboard bearings rearward of said rudder, said stern float having corrugations positioned in its cylindrical surface and parallel with its axis, said rear float having conically smooth surfaced ends to facilitate steering, the axes of all 15 said buoyant cylinders being horizontal to permit said cylinders to rotate in the direction of travel of said boat, and means for rotating said propeller shaft.

JOSEPH FITZGIBBON. 20
